UNITED STATES PATENT OFFICE

2,599,033

HIGH-FREQUENCY APPARATUS

Norman R. Wild, East Natick, Mass., assignor to
 Raytheon Manufacturing Company, Newton,
 Mass., a corporation of Delaware

Application November 15, 1946, Serial No. 709,987

3 Claims. (Cl. 219—47)

1

This invention relates to high-frequency apparatus, and more particularly to a steam and vapor shield for a microwave cooking device.

It has been found that, when food or other material positioned adjacent the open end of a hollow wave guide or horn is being heated by microwave energy propagating down the horn and out the open end thereof, several adverse effects are produced if the steam or vapor from the food is allowed to enter said horn.

In the first place, if microwave energy propagating down the horn impinges on clouds of steam therein, part of the energy is reflected from the steam, thus not reaching the food or at least causing appreciable distortion of the heat pattern produced by the energy in the horn. This heat pattern should be kept uniform or free from distortion if the desired even heating of the food is to be achieved.

In addition, steam or other vapors cause corrosion of the horn, which corrosion is, of course, undesirable.

Moreover, if steam is allowed to enter the horn, contacting the inner walls thereof, there will be an appreciable loss of heat from the food, through conduction by the steam from the food to the walls of the horn. This heat loss is undesirable because it prevents efficient utilization of the available energy for heating the food.

Furthermore, if steam is allowed to enter the horn, it will condense therein, producing moisture in the horn, on the inside thereof. Moisture in the horn greatly reduces the energy transmission efficiency of the same, because such moisture both reflects energy and absorbs energy, thus reducing the energy output (at the food end of the horn) relative to the energy input to the horn.

It is, therefore, an object of this invention to mask the interior of a hollow wave guide from steam or other vapors while at the same time permitting microwave energy to pass through the mask.

Another object is to provide a means for preventing entry of steam into the horn of a microwave cooker, this means not interfering with the normal energy-transmitting function of the horn.

The foregoing and other objects of the invention will be best understood from the following description of an exemplification thereof, reference being had to the accompanying drawing, wherein:

Fig. 1 is a vertical cross-section through a microwave cooker without a masking means, the cooker being shown in operation;

Fig. 2 is a cross-section through a microwave

2

cooker provided with a masking means in accordance with my invention; and

Fig. 3 is a section taken along line 3—3 of Fig. 2, on an enlarged scale.

Now referring to the drawing, and particularly to Fig. 1 thereof, a magnetron oscillator 1 is shown schematically as comprising a central cathode 2 surrounded by a conducting envelope 3 and a plurality of radially-extending vanes 4 which together constitute the anode structure. As is well known, such an oscillator is adapted to produce an output of high-frequency energy, for example in the microwave region of the frequency spectrum. The radio-frequency energy output 15 of the magnetron is coupled to a coaxial transmission line 5 by means of a suitable loop 6 which extends into the magnetron 1 between a pair of adjacent vanes 4. The inner conductor 7 of the transmission line may, for example, extend into one end of a hollow wave guide or horn 8, in order to serve as an exciting rod for said guide, thereby transferring high-frequency energy from line 5 to the guide.

Wave guide 8 may be square in cross-section, 25 as shown, or it may have any other desired cross-sectional configuration. Guide 8 is open at its lower end, so that it may be termed either a wave guide or a horn. Radio-frequency energy supplied to horn 8 at its upper end is adapted to propagate down said horn, radiating into space from the lower open end thereof. A container 9, which has the same cross-section as horn 8 and which is open at its upper end, is positioned adjacent the open end of horn 8, a body of food 10 30 to be heated or cooked being placed inside said container in such a position as to receive radio-frequency energy from the horn.

Radio-frequency energy is propagated down horn 8 and radiated from the lower open end 40 thereof, impinging on food body 10 and heating the same. As a natural consequence of this heating, clouds 11 of steam or other vapor are given off from the food and travel upwardly as shown, through the open end of the horn 8 and into said horn. As can be seen from an examination of Fig. 1, there are clouds of steam in the horn 8, which produce the adverse effects described in detail above.

Fig. 1 shows the resulting steam in the horn when no steam masking or shielding means is used. Now referring to Fig. 2, a device embodying a steam shielding or masking means according to my invention is shown. In this figure, parts the same as those of Fig. 1 are denoted by 55 the same reference numerals. A solid continu-

ous flat plate-like member 12, having an area slightly larger than the cross-sectional area of horn 8, is secured to said horn immediately below the lower open end of said horn, covering the open end of said horn. Member 12 is made of a material which is substantially transparent to radio-frequency energy, such as quartz, for example. If desired, the area of member 12 may be the same as the interior dimensions of horn 8, and said member may have any desired thickness.

Member 12 may be held in position over the mouth of the horn by any suitable means. For example, three elongated brackets 13 are secured to the horn 8, one to each of three sides thereof. The lower end of each of these brackets is shaped to embrace a corresponding edge surface of plate 12, holding the upper surface of said plate tightly against the lower surfaces of the walls of horn 8. To assemble plate member 12 on horn 8, said member is slid into place on brackets 13 from the side of the horn on which there is no bracket, the plate being held firmly in place due to the tight engagement of the upper surface thereof with the lower surfaces of the walls of the horn.

Container 14 holds food body 10 in position below member 12, the member 12 therefore being positioned between said body and the open end of guide or horn 8. In order to provide for the escape of steam from food 10, container 14 may be provided with a foraminous side wall 15.

Member 12 is transparent to radio-frequency energy, as stated above, so that energy propagating down horn 8 can pass therethrough to heat body 10. However, said member is not transparent to steam or other vapors 11, so that these cannot pass through plate 12 into the interior of horn 8, but instead pass harmlessly out into the external atmosphere through foraminous wall 15, as indicated in Fig. 2.

The plate 12, since it masks or shields the interior of the horn from steam, helps to keep the heat pattern at the food uniform or free from distortions which would be caused by steam in the horn. The plate also keeps the steam from corroding the horn, and keeps moisture from condensing in the horn. The plate prevents heat from being transferred, by the steam, from the food to the walls of the horn. In fact, all of the adverse effects which result from the presence of steam in the horn are entirely eliminated by the presence of plate 12, which is transparent to radio-frequency energy but is opaque to steam, in a masking position at the mouth of the horn.

Of course, it is to be understood that this invention is not limited to the particular details as described above, as many equivalents will suggest themselves to those skilled in the art. For example, any suitable fastening means other than that shown may be used to maintain plate 12 in position on horn 8. Also, any desired material which is suitable may be used for plate 12. Various other variations will suggest themselves. It is accordingly desired that the appended claims be given a broad interpretation commensurate with the scope of this invention within the art.

What is claimed is:

1. In a microwave cooking device, a hollow metallic wave guide having an open end, means for supplying microwave energy to said guide,

means for supporting an energy-absorbing body closely adjacent the open end of said guide to receive energy therefrom, said body producing vapors when the same is heated, and a vitreous masking member covering the open end of said guide, said member being substantially transparent to microwave energy and being positioned between said body and the open end of said guide, and said supporting means being provided with openings for allowing said vapors to escape therefrom, said opening being less than one-eighth of a wave length of the frequency of said microwave energy.

2. In a microwave cooking device, a hollow metallic wave guide having an open end, means for supplying microwave energy to said guide, means for supporting an energy-absorbing body closely adjacent the open end of said guide to receive energy therefrom, said body producing vapors when the same is heated, and a vitreous masking member covering the open end of said guide, said member being substantially transparent to microwave energy and being positioned between said body and the open end of said guide, said supporting means being metallic and substantially surrounding the end of said guide and being provided with openings for allowing said vapors to escape therefrom, said openings being less than one-eighth of a wave length of the frequency of said microwave energy.

3. In a microwave cooking device, a hollow metallic wave guide having an open end, means for supplying microwave energy to said guide, means for supporting an energy-absorbing body closely adjacent the open end of said guide to receive energy therefrom, said body producing vapors when the same is heated, and a vitreous masking member covering the open end of said guide, said member being substantially transparent to microwave energy and being positioned between said body and the open end of said guide, and said supporting means being provided with openings for allowing said vapors to escape therefrom, said opening being less than one-eighth of a wave length of the frequency of said microwave energy whereby microwave energy is substantially prevented from escaping from said cooking device.
